Primary Examiner — Garth Rademaker*Assistant Examiner* — Katie Mroczka(74) *Attorney, Agent, or Firm* — Donald J. Ranft; Kristen A. Mogavero; Collen IP(57) **CLAIM**

The ornamental design for a food cone, as shown and described.

DESCRIPTION

FIG. 1 is a perspective view of a food cone according to the first embodiment of my new design;

FIG. 2 is a front elevational view thereof, the rear, the left side, and the right side elevational views being identical to the front elevational view;

FIG. 3 is a top plan view thereof;

FIG. 4 is a bottom plan view thereof;

FIG. 5 is a perspective view of a food cone according to the second embodiment of my new design;

FIG. 6 is a front elevational view thereof, the rear, the left side, and the right side elevational views being identical to the front elevational view;

FIG. 7 is a top plan view thereof; and,

FIG. 8 is a bottom plan view thereof.

The broken lines in FIGS. 1, 3, 5 and 7 illustrate portions of the food cone which form no part of the claimed design.
